UNITED STATES PATENT OFFICE.

ALONZO E. CLOUGH, OF MADISON, SOUTH DAKOTA.

SPLINT.

1,221,289.

Specification of Letters Patent.

Patented Apr. 3, 1917.

Application filed August 2, 1916. Serial No. 112,773.

To all whom it may concern:

Be it known that I, ALONZO E. CLOUGH, a citizen of the United States, residing at Madison, in the county of Lake and State 5 of South Dakota, have invented certain new and useful Improvements in Splints, of which the following is a specification.

This invention relates to splints and more particularly to that class of splints used on 10 fractured limbs and has for one of its objects the provision of a device of this character that is adjustable in length and also provides for extending the injured limb.

Another object is to provide a device of 15 this class that may be adjusted to stout or lean persons so as to keep the splint in the center of the limb.

A further object is to provide a device 20 that will prevent the patient assuming injurious positions during treatment, and is so constructed that it will aid in supporting the injured limb when the patient is turned on his side for bathing or other purposes.

25 Other objects such as simplicity, durability, lightness, cheapness in manufacture, and the general improvement of the art will be brought out in the following specification and illustrated in the accompanying drawing in which:

Figure 1 is a front view of the device in operative position,

Fig. 2 is a side view of the same, and

35 Fig. 3 is a fragmentary view of the bottom cross piece of Fig. 1, showing the under side.

Referring more particularly to the drawing, my device comprises side brace member 1 consisting of parts 2 and 3 having a plurality of holes 4 and adjustably held together by bolts 5 passing through the holes 4.

The part 2 of the side brace member 1 is secured to bottom cross piece 6 and has 45 braces 7 secured to its lower end and abutting the bottom cross piece 6. The cross piece 6 extends an equal distance from each side of the side brace member 1 and a supporting brace 8 extends from the part 2 of the side brace member 1 to the one end of the bottom cross piece 6.

50 A member 9 having a plurality of holes 10 is held adjustably crosswise on the side brace member 1 by bolts 12 and is adapted 55 to be adjusted to center the device when applied to stout or thin persons. A body strap

13 passes over the member 9 and is secured thereto by one of the bolts 12.

The part 3 of the side brace member 1 has apertures 14 adjacent its top and a 60 perineal band 15 is adapted to be secured therein.

An extension member comprises a foot member 16 and flexible cords 17 which are passed through apertures 18 in the bottom 65 cross piece 6 and are secured together by knotting. A roller bar 19 is passed between the cords 17 and held in place by the securing pin 20 inserted in one of the apertures 21. 70

The operation of the device is as follows: The splint is adjusted to the required length preferably about 6 inches longer than the limb. The member 9 is then adjusted to 75 suit the size of the person whether stout or thin so as to center the device on the injured limb.

The splint is then ready to be applied, and when placed in position, the perineal band 15 put in place and drawn tight and 80 held by hard knots and the body strap 13 secured, the device is firmly and securely in place, and the foot member 16 is then secured to the patient's foot by adhesive plaster which extends from the knee joint and 85 is reinforced at the bottom, and is held in place by its own adhesiveness and a gauze bandage secured by adhesive strips.

The operation of extending the limb may now be performed and consists in simply 90 turning the roller bar 19 until the desired extension is obtained and securing it in place by the pin 20.

It will be apparent that my device may be and is adapted to be used on either the 95 right or left limb of the patient.

It will of course be understood that I may construct the device of any material and that I may make any changes in construction within the scope of the appended 100 claims without departing from the spirit of my invention.

Having thus described my invention what I claim is:

1. An extension splint comprising a side 105 brace member, said member being composed of two pieces adapted to be adjusted one upon the other, a bottom cross piece, said bottom cross piece extending an equal distance from each side of said side brace to prevent the patient to whom it is affixed from rolling, a perineal band secured to said side 110

brace, a body strap for holding the top of said splint in position, a centering member adjustably secured to said side brace member and adjustable crosswise thereon, and 5 means for extending a fractured limb.

2. An extension splint comprising a side brace member, a bottom cross piece, said bottom cross piece extending an equal distance from each side of said side brace, a perineal band secured to said side brace, a body strap adjacent the top of said side brace, means for centering said splint, said means comprising a centering member adjustably secured to said side brace and coöperating 10 with said body strap, and means mounted in said bottom cross piece for extending a fractured limb.

Copies of this patent may be obtained for five cents each, by addressing the "Commissioner of Patents, Washington, D. C."

3. An extension splint comprising a side brace member, a bottom cross piece, a perineal band secured to said side brace, a body strap adjacent the top of said side brace, means for extending a fractured limb, a centering member having a plurality of apertures therein, said centering member being adapted to be adjusted horizontally 20 of said side brace and held in adjusted positions by set screws passing through selected ones of said apertures, and said member when secured in position being adapted to coöperate with said body strap. 25

In testimony whereof I hereunto affix my signature.

ALONZO E. CLOUGH.
